Primary Examiner — Derrick Holland*(74) Attorney, Agent, or Firm* — The Law Office of Patrick F. O'Reilly III, LLC(57) **CLAIM**

The ornamental design for a support member for photovoltaic modules, as shown and described.

DESCRIPTION

FIG. 1 is a top-rear perspective view of a support member for photovoltaic modules showing my new design;

FIG. 2 is a top-front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is bottom-front perspective view thereof; and,

FIG. 10 is bottom-rear perspective view thereof.

The broken line portions of the drawing figures are included to show unclaimed subject matter only and form no part of the claimed design.

1 Claim, 8 Drawing Sheets(56)
